FRINGE SUPPORT FOR USE IN PACKING
FRUITSJames W. Trew, Gettysburg, Pa., assignor to Rice,
Trew & Rice Co. Inc., Biglerville, Pa., a corpora-
tion of Pennsylvania

Application July 15, 1937, Serial No. 153,854

3 Claims. (Cl. 226—17)

This invention relates to a fringe support for use in packing fruit.

The trade recognizes the fact that in the distribution of apples, peaches and kindred fruit the sales are materially increased and better prices can be obtained when the packages are made attractive. The trade also fully appreciates the fact that a highly attractive package is made by the use of a fringe strip but heretofore considerable expense has been involved in providing a fruit package employing a fringe strip due to the increased labor cost.

It is an object of the present invention to provide means whereby a fringe strip can be comprised in a fruit package with a substantial elimination of any additional cost.

It is also an object of the invention to provide means whereby a fringe strip can be effectively maintained in required position upon a facing form or the like so that the package can be completed in accordance with the methods now generally employed.

A still further object of the invention is to provide a support for use in connection with a fringe strip which operates to effectively maintain the strip in applied position upon a facing form or the like and which also operates to prevent lateral distortion of the fringe strip.

The novel features of my invention will hereinafter be definitely claimed.

In order that my invention may be the better understood, I will now proceed to describe the same with reference to the accompanying drawing, wherein:—

35 Figure 1 is a vertical sectional view taken through a fringe support constructed in accordance with an embodiment of my invention and in applied position;

Figure 2 is a vertical sectional view showing the 40 application of the conventional tub and liner after the fringe strip has been applied;

Figure 3 is a view in top plan of the support as herein disclosed.

As disclosed in the accompanying drawing, F 45 denotes a facing form of a conventional type upon which is adapted to be arranged a facing layer of apples, peaches or kindred fruit as is well known in the methods of packing now generally in use. In the present known methods of packing, this facing form has employed therewith a liner L within a tub T, said assembled liner L and tub T being placed upon the facing form F after the fruit layer has been arranged upon the form. Then, after the desired fruit has been 50 poured within the liner upon the face layer of

fruit the tub T is removed and a basket inverted over the liner L and its content. The basket with the facing form F is then upended resulting in a properly packed basket of fruit presenting a smooth and attractive top or face layer of fruit. 5 The attractiveness of the package, however, as well as its sale value are materially increased by employing a fringe strip S and which strip, when applied, presents a plurality of flaps 1 of desired configuration which overlie the marginal portion 10 of the top or facing layer of fruit.

The use of such a fringe strip is well known but considerable difficulty has heretofore been encountered in facilitating the desired placement of this fringe strip so that a fruit package including 15 such a strip may be produced with substantially no increase in the cost of labor.

In the embodiment of the invention as herein disclosed I provide an annular member M of suitable material and in the form of a truncated 20 cone. The diameter of the member M at its lower or larger end is such as to permit the member or ring M to be snugly engaged around an upstanding continuous flange 2 comprised in the structure of the facing form F whereby the member or ring M is properly positioned. This member or ring M is of relatively short length or of a length substantially equal to the width of the body portion of a fringe strip S. As herein disclosed, the fringe strip S is of a split type and 30 has the conventional flaps 1 which flex inwardly for close contact with the upper face of the facing form F when the strip is in applied position. The extremities of this strip S also overlap and said overlapping portions are provided with interlocking means, as at 4, to maintain the same against 35 separation.

The upper marginal portion of the member or ring M at predetermined points spaced there-around and preferably at equi-distantly spaced 40 points is provided with the inwardly disposed and downwardly facing hook members 5 under which the upper marginal portion of the applied fringe strip S is adapted to be engaged. By this means the strip S is maintained in effective position upon 45 the facing form F and said strip S is also held against lateral displacement or buckling inwardly of the facing form whereby the strip S is further maintained in effective placement upon the form F. In other words, the member or ring M is so 50 constructed and arranged and of such dimensions that it provides effective means to prevent the top edge or marginal portion of an applied fringe strip S from lifting out of the facing form during the facing operation.

After the face layer of fruit is completed in the facing form F the member or ring M is removed. The fruit comprised in the facing layer upon the form F will coat with the fringe strip S to maintain the same against displacement while the assembled liner L and tub T are applied upon the facing form F and in surrounding relation with respect to the applied fringe strip S. The fruit package is then completed in accordance 5 with the well known methods.

From the foregoing description it is thought to be obvious that a fringe support for use in packing fruit constructed in accordance with my invention is particularly well adapted for use by 10 reason of the convenience and facility with which it may be assembled and operated, and it will also be obvious that my invention is susceptible of some change and modification without departing from the principles and spirit thereof and for 15 this reason I do not wish to be understood as limiting myself to the precise arrangement and formation of the several parts herein shown in carrying out my invention in practice except as hereinafter claimed.

20 25 I claim:—

1. Means for retaining a fringe strip upon a facing form during a fruit packing operation comprising a supporting member to be mounted upon the facing form exteriorly of the fringe 30 strip and with the fringe strip in close contact

therewith, and inwardly disposed and downwardly facing hook members carried by the upper portion of the supporting member to engage over the upper edge of a fringe strip to hold said fringe strip against movement away from the facing 5 form.

2. Means for retaining a fringe strip upon a facing form during a fruit packing operation comprising a supporting member to be mounted upon the facing form exteriorly of the fringe strip 10 and with the fringe strip in close contact therewith, and inwardly disposed and downwardly facing hook members carried by the upper portion of the supporting member to engage over the upper edge of a fringe strip to hold said fringe 15 strip against movement away from the facing form, said hook members being equi-distantly spaced around the supporting member.

3. Means for retaining a fringe strip upon a facing form comprising a supporting member to 20 be mounted upon a facing form and surrounding the fringe strip, and inwardly disposed and downwardly facing hook members carried by the upper portion of the supporting member to engage over the upper edge of the fringe strip to hold said 25 fringe strip close to the supporting member to permit ready application of a facing layer of fruit upon the facing form and within the field defined by the fringe strip held by the supporting member.

JAMES W. TREW. 30
